UNITED STATES PATENT OFFICE.

CONRAD A. RYAN, OF CANTON, MINNESOTA.

GRINDING MACHINE FOR MILL BURRS OR OTHER ARTICLES.

Application filed October 7, 1925. Serial No. 60,995.

This invention has for its object to provide a highly efficient grinding machine for mill burrs or other articles having a relatively flat circular surface or a flat surface having up-
standing cutting edges thereon.

At the present time, the grinding burrs employed in most rural flour and feed mills are usually discarded when they become pitted or dulled. This invention provides a simple grinding machine especially adapted to grind mill burrs having upstanding cutting edges on a disk-like or annular surface, usually radially and concentrically arranged of either flat or beveled type.

It is a further object of the invention to provide a device of this kind, wherein the burr or other article to be ground is mounted on a rotating carrier member and subjected to a transversely movable grinding wheel rotating in the opposite direction preferably and adapted to move across a sufficient portion of the rotating burr or other article to sharpen all cutting edges thereon.

It is a still further object in such a device to provide a carrier member adapted to be slightly tilted to one side or the other, whereby the angle between the axis thereof and the axis of the grinding member may be varied to grind bevels of different pitch on the burrs or other articles.

An additional object of the invention is to provide efficient means for driving the rotating parts, regulating the position of the same with respect to each other, and moving the grinding wheel across a portion of the burr mounted on the carrier.

These and other objects of the invention will be apparent from the following description made in connection with the accompanying drawings, wherein like characters refer to similar parts throughout the several views, and in which,

Fig. 1 is a plan view of the preferred form of the invention;

Fig. 2 is a rear elevation of the same;

Fig. 3 is a detail elevation showing the carrier plate with fragments of a burr mounted thereon; and

Fig. 4 is a cross section, on an enlarged scale, taken on the line 4—4 of Fig. 3.

In the drawings, a relatively heavy rectangular frame is provided, comprising a pair of spaced side members or timbers 5, a pair of transverse end members 6 and 7, respectively, secured across the ends of side members 5, and intermediate parallel spaced

transverse members 8, 9 and 10, respectively, secured across side members 5, members 9 and 10 projecting for some distance beyond one side of the frame, and member 9 being substantially disposed centrally of the frame. A longitudinally disposed member 11 is secured across members 10 and 6 parallel with the sides 5 of the frame, and having one of its ends projecting beyond member 10 slightly beyond the center line of the space between members 9 and 10.

A pair of horizontally aligned transverse bearings 12 are provided, one secured to one of the side members 5 and one secured adjacent the projecting end of member 11, and a third bearing 13, in alignment with bearings 12, is secured to the opposite side member 5. The grinding shaft 14 is journaled in bearings 12 and 13 having one of its ends normally projecting a considerable distance beyond the bearing 13, the purpose of which will later be explained. A driving pulley 15 is keyed in a relatively long slot 14^a to the shaft 14, bearings 12 acting as keepers for said pulley, and slot 14^a permitting the grinding shaft to be moved longitudinally in either direction. Pulley 15 is driven by an endless belt 16 connected to a suitable source of power. A swiveled collar 17 is rigidly secured to one end of shaft 14 and a screw 18 having at its inner end the enlarged head 18^a, is swivelly connected to said collar. The screw 18 is engaged by the threaded bearing 19^a carried by a strap 19, which is secured across the projecting ends of members 9 and 10. Crank lever 20 is rigidly secured to the outer end of screw 18 and obviously may be manipulated to move the shaft 14 longitudinally in either direction. A grinding wheel 21 is rigidly secured to the shaft 14 and is adapted to be moved with the grinding shaft between member 11 and one of the side members 5.

A bearing 22 is provided with a pair of arcuate slots 22^a at either side thereof, through which slots nutted bolts 23 pass, permitting said bearing to swing horizontally on the frame member 9. A pair of horizontally aligned bearings 24 and 25 are mounted on the transverse frame members 7 and 8, respectively, slidably secured to said members by bolts which pass through the slots 24^a and 25^a, respectively, at the sides of said bearings. A carrier shaft 26 is journaled in the bearings 22 and 25, having its ends projecting therebeyond, and having rig-

12

idly and detachably mounted at its inner end a carrier plate or disk 27, which is provided with a plurality of threaded recesses or sockets 27^a. The burrs or other articles to be ground may be secured to the carrier plate 27 by means of a plurality of bolts 27^b. Most of the standard burrs used in mills comprise several arcuate sections A having therein triangularly arranged countersunk 10 apertures to accommodate the securing bolts. By providing a plurality of threaded recesses 27^a, burrs of different sizes, having differently arranged apertures therein, may be readily accommodated. The axis of carrier 15 shaft 26 is obviously transversely disposed with reference to the fixed axis of grinding shaft 14 and, as shown in Figs. 1 and 2, the burr A mounted on carrier plate 27 is adapted to be engaged by the grinding edge 20 of the wheel 21. The bearing 24 is threaded to receive a screw 28, the inner end of which contacts the adjacent extremity of shaft 26. A coiled spring 29 is interposed between the bearing 24 and the collar 30 rigidly secured 25 adjacent the extremity of shaft 26, to normally impel the carrier shaft longitudinally outward against the working end of screw 28. A crank lever 31 is rigidly secured to the end of screw 28 by the manipulation of which carrier shaft 26 and carrier plate 27 30 may be longitudinally adjusted. The shaft 26 may be tilted in either direction, bearing 22 pivoting and bearing 24 sliding in an arc. Such tilting is effected by means of a screw 32 having at its inner end the enlarged head 32^a swiveled to the collar 24^a carried by bearing 24, said screw 32 having threaded engagement with the bearing 33 and having rigidly secured to the end thereof the crank 35 lever 34.

A transverse driving shaft 35, journaled in oppositely aligned transverse bearings 26, carries a worm 35^a engaging the worm gear 37 on shaft 26. The shaft 35 is projected 40 beyond one side of the frame rigidly carrying the pulley 28, which is driven from the grinding shaft 14 by means of the endless member 39. A hand wheel 40, having a plurality of radially disposed handles, is rigidly secured to the shaft 26, permitting the shaft to be rotated manually by the operator when it is desired to dispense with the worm and driving shaft 35. The worm gear 37 drives the carrier shaft in the reverse 45 direction from the rotation of the grinding wheel, thus increasing the efficiency of the grinding of the burr mounted on the carrying plate.

The operation of the machine is probably 50 obvious from the foregoing description in connection with the drawings, but may be briefly summarized as follows:—

The carrying plate 27 is first detached by unloosening its set screw and the several sections A of the burr or other article to be

ground is bolted to the face thereof by utilizing the proper threaded sockets 27^a. The carrier 27 is then again rigidly secured to the end of shaft 26 and said shaft properly tilted so that the grinding edge of the wheel 21 70 will be substantially normal to the surface or edges of the burr A to be ground. The carrier plate 27 is then adjusted longitudinally by manipulating the crank 31 until the grinding wheel will properly engage the 75 burr. The power is then turned on and the grinding wheel is moved longitudinally from one side to the other across one side of the annular or disk-like face of the burr A by manipulating the crank 20. As illustrated, the carrier shaft 26 is rotated in the opposite direction from that of the grinding wheel driven from the driving shaft 35 connected directly to the projecting end of the grinding shaft 14, but obviously other means 85 may be employed for connecting said grinding shaft 14 with the carrier shaft 26.

Many of the standard burrs employed in feed and flour mills have convexly beveled cutting edges b and c, respectively, as illustrated in Fig. 4, the angles of said bevels, however, being exaggerated in the drawings. It will be obvious that, by tilting the carrier shaft 26 slightly, by manipulating the crank 34, the burr to be ground will be held at the proper angle with respect to the grinding wheel, to permit the bevel to be correctly engaged by the grinding edge of said wheel. The grinding shaft 14 is then longitudinally moved, thereby causing the grinding wheel 21 to pass across the bevel desired to be ground, while the latter is in rotation in the opposite direction. The shaft 26 may then be tilted in the opposite direction by means of the manipulating crank lever 34, whereupon the other bevel on the burr may be ground.

It will be apparent from the foregoing description that applicant has a simple but highly efficient machine for grinding mill 110 burrs or other analogous articles comprising few parts, being durable in structure and capable of wide employment.

Extensive actual usage of the device has shown it to be successful for all of the purposes intended.

It will, of course, be understood that various changes may be made in the form, details, proportions and arrangement of parts without departing from the scope of the 120 invention.

What is claimed is:—

1. A machine of the class described comprising a support, a carrier shaft journaled on said support having a rotary carrier member mounted on the inner end thereof, a grinding shaft journaled on said support and extending transversely to said carrier shaft, a grinding wheel on said grinding shaft, means for moving said grinding wheel 125

- in both directions across a portion of said carrier member, and means for adjusting said carrier shaft longitudinally including a longitudinally movable worm engaging the 5 outer end of said carrier shaft, driving connections between said grinding shaft and said carrier shaft, and resilient means for impelling said shaft outwardly away from said grinding wheel.
- 10 2. A machine of the class described having in combination a frame, a pivot bearing and a slideable bearing mounted thereon, said last mentioned bearing being slideable in an arc substantially concentric with the axis of said 15 pivot bearing, a carrier shaft journaled in said bearing and having a carrier member mounted on one end thereof, a grinding shaft having a grinding wheel thereon mounted for engagement with an article 20 cured to said carrier member, means for driving said grinding and carrier shafts and a traveling worm mounted on said frame having swivel connection with said slideable bearing for adjusting the same.
- 25 3. A machine for grinding mill burrs or other articles having in combination a substantially rectangular frame, a pivot bearing mounted substantially centrally thereof, a slideable bearing mounted in longitudinal 30 alignment therewith, a carrier shaft mounted for rotation in said bearings, a rotary carrier member mounted on the inner end of said shaft, a grinding shaft rotating on an axis transverse to the axis of said carrier shaft, a grinding wheel on said grinding shaft, means for moving said grinding wheel across a portion of the rotating surface of the article to be ground, means for swinging said shaft on said pivot bearing, a driving shaft geared to said carrier shaft and substantially parallel with said grinding shaft, and means for connecting said grinding shaft with said driving shaft to drive the latter. 35
4. In a machine of the class described a support, a pivot bearing mounted thereon, a bearing also mounted on said support slideable substantially in an arc concentric with the axis of said pivot bearing, a carrier shaft journaled in said bearings and 40 having a carrier member secured to one end thereof, a threaded bearing disposed adjacent the opposite end of said carrier shaft and mounted for slideable movement substantially in an arc concentric with the axis of 45 said pivot bearing and a worm adapted to engage the adjacent end of said carrier shaft to adjust the same longitudinally, a grinding shaft disposed transversely to the axis of said carrier shaft carrying a grinding 50 wheel, and means connected to said first mentioned slideable bearing for adjusting the same. 55

In testimony whereof I affix my signature.

CONRAD A. RYAN.
